[57] CLAIM

The ornamental design for a screwdriver tip, as shown and described.

DESCRIPTION

FIG. 1 is a front elevational view of a screwdriver tip showing my new design with the rear elevational view being identical;

FIG. 2 is an enlarged bottom plan view thereof;
FIG. 3 is an enlarged right side elevational view thereof with the left side elevational view being identical; and,
FIG. 4 is a perspective view thereof.

The broken line showing of the handle and shank are for illustrative purposes only and form no part of the claimed design.
